UNITED STATES PATENT OFFICE.

ALFRED L. MACK, OF CANTON, OHIO, ASSIGNOR OF ONE-HALF TO MARTIN L. BEST, LEVI L. MILLER, AND JACOB MILLER, OF SAME PLACE.

RESERVOIR FOR BURNING-FLUIDS.

SPECIFICATION forming part of Letters Patent No. 286,211, dated October 9, 1883.

Application filed June 13, 1883. (Model.)

To all whom it may concern:

Be it known that I, ALFRED L. MACK, a citizen of the United States, residing at Canton, in the county of Stark and State of Ohio, 5 have invented certain new and useful Improvements in Reservoirs for Burning-Fluids; and I do hereby declare that the following is a full, clear, and exact description of the same, reference being had to the annexed drawings, 10 making a part of this specification, and to the letters and figures of reference marked thereon.

Figure 1 of the drawings is a longitudinal vertical section of the invention; Fig. 2, a detail view, in perspective, of the funnel-shaped stationary tank; Fig. 3, a similar view of the pipes and valve, and Fig. 4 a view showing the application of the invention to a street-lamp.

20 This invention relates to certain new and useful improvements in reservoirs for holding and supplying oil, gasoline, or other burning-fluids to street-lamps, vapor-stoves, and other devices of a similar character, the object of 25 the present invention being to provide such a reservoir as will be simple in its construction, inexpensive in its manufacture, capable of being readily employed in connection with any of the devices above enumerated, and 30 which, when emptied of the oil or fluid, may be easily removed and a filled one substituted, thereby saving time and obviating the danger of explosions incidental to the careless filling of the reservoirs while in place upon 35 the stove or lamp with the flame still in ignition; also, by the construction hereinafter described, the fluid has no means of escape until the reservoir is placed in its proper position for use, the fluid being also prevented 40 from evaporation and from water or other impurities entering therein when said reservoir is exposed to weather or used in a dusty place, and the flow of the oil or fluid to the burner being free and uninterrupted, a clear and 45 steady flame is thus insured.

The invention therefore consists in forming a portable reservoir in such a manner as to fit and rest upon a stationary tank adapted to be secured to the service-pipe of the lamp, 50 stove, or other similar device, said reservoir

being provided with suitable feed and air pipes, having a valve or stopper kept in its closed position by a spring or other like fastening, said feed and air pipes being preferably removable from the reservoir, substantially as shown in the accompanying drawings, and hereinafter described. 55

In the drawings, A represents the reservoir, preferably of a cylindrical form, having its bottom a set in a sufficient distance to provide a flange or rim which fits over and around the annular portion b of a tank, B, adapted to be permanently secured to the service-pipe C of a lamp, stove, or other similar device, said tank being preferably funnel-shaped, and 60 is provided with a top or cover, D, having an opening, e, to admit the entrance of the screw-capped portion d of the reservoir-bottom a when said reservoir is placed in position for use. 65

To the screw-cap E is suitably connected an air-pipe, F, extending up inside to nearly the top of the reservoir, and projecting outwardly from said cap a short distance, as shown at e. 70 Adjoining this air-pipe F is the feed-pipe G, which terminates at the screw-cap, as shown in Fig. 1. Secured to these pipes F G is a hinged valve, H, which prevents the oil or fluid from splashing out when the reservoir is being carried from one place to another, a suitable spring, f, or other like fastening, keeping said valve in its closed position. 75

To fill the reservoir, the screw-cap E is removed and the oil or fluid poured in through the opening which it covers. After filling, the 80 cap is replaced and the pipes F G closed by the valve H, and, if necessary to transport the reservoir, the same is carried top downward, said top being made flat in order to give it a firm rest when laid down in its reversed position. 85

When the reservoir is to be placed in position for use, the valve is opened and said reservoir inverted and placed upon the tank B, which is permanently attached to the service-pipe C of the lamp or stove. The oil or fluid now feeds down through the pipe G into the tank B, air being admitted to the reservoir through the pipe F until said oil or fluid rises 90 and covers the ends of both pipes, thus pre- 95 100

venting the further admission of air, and thereby stops the oil or fluid from feeding faster than it is consumed by the burner, the top or cover D of the tank preventing the vapor from escaping, the opening in said top being only large enough to admit the screw-capped portion d of the reservoir's bottom, and said portion tapering in order to secure a tight joint.

10. When the oil or fluid is exhausted, the reservoir may be readily removed from the stationary tank and a filled one substituted.

15. It will be seen by the above description that a reservoir applicable to devices enumerated is provided that is self-sealing, self-regulating, and which, when filled, may be carried or transported from place to place without danger of its contents leaking or spilling; also, when in use, its several parts cannot become 20 clogged by dust or dirt, and, owing to its construction, water is prevented from entering or evaporation taking place, this being of great advantage when the device is employed in connection with street or other lamp exposed to 25 the weather, thereby lessening the danger of explosions by ignition of escaping vapor or careless refilling of the reservoir while the flame may be burning, it being impossible to fill said reservoir without removing it from 30 the stationary tank.

Having now fully described my invention, what I claim as new, and desire to secure by Letters Patent, is—

35. 1. The reservoir herein described, adapted to fit over and around a tank capable of being permanently secured to the service-pipe of a lamp, stove, or other like device, the feed and air pipes arranged substantially as shown, and provided with a valve or stopper adapted to 40 be kept in its closed position by a spring or other suitable fastening, as and for the purpose specified.

45. 2. A reservoir for containing oil or other burning-fluid, having its bottom set in to form a flange or rim to fit over and upon a suitable tank adapted for permanent connection to the service-pipe of a lamp, stove, or other similar device, said bottom having an opening provided with a screw-cap, and air and feed pipes 50 connected thereto, substantially as and for the purpose described.

3. The tank herein described, adapted for

permanent attachment to the service-pipe of a lamp, stove, or similar device, having its lower portion preferably funnel-shaped and 55 its upper portion of an annular form, and provided with a top or cover having an opening for the admission of the depending portions of a reservoir, adapted to fit over the annular portion of said tank, substantially as and for 60 the purpose set forth.

4. The feed and air pipes of the reservoir herein described, secured to a screw-cap fitting upon an opening in said reservoir's bottom, the air-pipe extending up into the reservoir and projecting outwardly from the screw-cap, the feed-pipe equal only in length to the projecting portion of the air-pipe, and said pipes provided with a suitable valve or stopper having a spring or like fastening to retain it in its closed position, substantially as 70 shown and described.

5. The combination, with the reservoir herein described, having its bottom set in to form a flange, and provided with an opening adapted to receive a screw-cap, having secured thereto or formed therewith suitable air and feed pipes, of a funnel-shaped tank having its upper portion of an annular form, and provided with a top or cover having an opening to admit the screw-capped portion of the reservoir, said tank being capable of permanent connection with the service-pipe of a lamp, stove, or other similar device, substantially as specified.

6. The reservoir provided with an opened bottom set in to form a flange or rim, the screw-cap having the feed and air pipes secured thereto, the valve or stopper for closing said pipes, the tank to receive and sustain said reservoir, and provided with a top having an opening in which fits the screw-capped and tapered portion of the reservoir's bottom to form a tight joint, said tank being adapted for permanent attachment to street-lamps, vapor-stoves, or similar devices, substantially as and for the purpose set forth.

In testimony that I claim the above I have hereunto subscribed my name in the presence of two witnesses.

ALFRED L. MACK.
